J. W. DAHL ET AL

WOOL CUTTING MACHINE

Filed Aug. 27. 1920

UNITED STATES PATENT OFFICE.

JOHN W. DAHL, OF MELROSE, AND EDWARD D. MORGAN, OF QUINCY, MASSACHUSETTS,
ASSIGNORS TO SEVERN MILLS CO., OF BOSTON, MASSACHUSETTS, A CORPORATION
OF MASSACHUSETTS.

WOOL-CUTTING MACHINE.

Application filed August 27, 1920. Serial No. 406,455.

To all whom it may concern:

Be it known that we, JOHN W. DAHL and EDWARD D. MORGAN, respectively a citizen of the United States and a subject of the 5 King of Great Britain, and residing at Melrose, in the county of Middlesex and State of Massachusetts, and at Quincy, in the county of Norfolk and State of Massachusetts, have invented new and useful Im-
10 provements in Wool-Cutting Machines, of which the following is a specification.

The object of the present invention is to provide a machine which may be used for cutting wool, as delivered in the fleece, into 15 relatively short lengths. In fact, the object of the invention is to provide a machine which may be employed as one of the instrumentalities in the process of treating wool described in our co-pending applica-
20 tion Serial No. 406,456, filed concurrently herewith. As explained in said application, to which reference may be had, it is desirable to cut the fleece wool into fibers of relatively short length, say from one and one-
25 half to three inches. There are certain grades of sheep in which the fiber grows from six to twelve inches in length, according to the part of the body to which it is attached. Such wool, as grown upon the
30 sheep, becomes impregnated and matted with grease, suint and many different foreign substances, so that it is difficult to handle and to cut. The present invention, as indicated, consists of a machine by which
35 this cutting of the greasy matted wool may be easily accomplished.

On the accompanying drawings,—

Figure 1 represents in side elevation a machine embodying our invention.
40 Figure 2 represents a longitudinal vertical section through the same.

Figure 3 represents the machine in plan view with the protective hood or casing removed from the knife.

45 Figure 4 is a detail view illustrating the arrangement of the cylinder knives in relation to the stationary knife.

The frame-work of the machine may be formed as desired. It is illustrated, how-
50 ever, as consisting of two end frames 10, 10, which may be suitably braced together, and which support a rigid cross bar 11 upon which rests a stationary shear blade 12. Any suitable means may be provided for
55 effecting the removal of the stationary blade

for grinding purposes or to permit its ad-
justment relatively to the bar 11 on which
it is supported. For cooperation with the
stationary blade, we employ a rotary cutter
indicated as a whole at 13 and securely 60
mounted upon a shaft 14 journaled in the
end frames 10, 10, by any suitable form of
bearings. Any number of blades may be
secured to the rotary cutter, this depending
upon the speed at which the cutter is ro- 65
tated, the diameter of the cutter, and the
desired length of staple of the cut wool. As
shown, however, the rotary cutter is pro-
vided with three blades 15. The body of
the cutter is recessed as at 16, the bottom of 70
each recess being curved and at its median
line approaching the shaft 14. One end of
each recess is formed by one of the knife
blades. Each knife blade is located in a
socket 17 and is rigidly secured in place by 75
bolts 18 and nuts 19. In effect, the cutter
body may be considered as having three
arms which extend substantially from end to
end of the cutter body and are connected by
integral disks 20, 20, as shown in Figure 3. 80
These disks form the end walls of the re-
cesses 16. We regard the provision of the
knife body with these recesses as impor-
tant, as it permits the matted wool to be fed
the desired distance across the edge of the 85
stationary blade 12 before it is severed by
one of the blades of the rotary knife.

Because of the character of the material
being cut, a shearing action thereon is de-
sirable, and, consequently, each knife blade 90
15 is preferably arranged at an angle to a
line on the periphery of the cutter parallel
with the axis, so that, as each blade 15 ap-
proaches the stationary blade 12, the cut-
ting action will progress from one end to the 95
other of the coacting blades.

The wool may be fed to the action of the
cutters just as it comes in the fleece, or
the fleece may be more or less separated
and forked apart before it is fed to the 100
cutter. In any event, however, means must
be provided for feeding the staple uniform-
ly to the action of the cutting blade. For
this purpose, we employ a feed table 21
and a co-acting feed roll 22. It will be 105
understood, of course, that the feed table
may be of any desired length upon which
the operator may place the staple and feed
it along until it is gripped by the feed
roll, or, if desired, supplemental feeding 110

mechanism of any suitable sort may be used for carrying the material along the feed table until it reaches the grip of the feeder roll 22. The feed table is illustrated 5 as being provided with side boards 23 and as being supported by a brace or bracket 24. The feed roll 22 is preferably provided with a plurality of points or pointed projections which may be conical or pyramidal 10 in form, and which are arranged in staggered series, as indicated at 25, 26 in Figure 3, so as to ensure that the staple will be properly penetrated, gripped and fed to the action of the cutters. If desired, these 15 points or projections may be formed on the peripheries of separate rings or disks clamped together and secured upon a transverse shaft 27. At the ends of the roll, there may be flanges or disks 28 which are 20 slightly greater in diameter than the pointed portions of the roll, and which fit closely within the side boards of the feed table. The feed roll is so mounted that it rests by gravity on the material being fed so 25 that it has a yielding pressure thereon. For this purpose, the shaft 27 is journaled in two angular arms 29, 29, said arms being themselves pivoted on a shaft 30, which latter may be journaled in bearings 31 on 30 extensions 32 from the frame-work. The braces or struts 24, hereinbefore referred to, act as supports for these extensions 32. The shaft 30 acts as an intermediate shaft for the purpose of transmitting power from 35 the cutter shaft 14 to the feed roll shaft 27. To this end, the shaft 14 and the shaft 30 are provided with pulleys 33, 34, on which a belt 35 is stretched; and the shaft 30 has a sprocket wheel 36 from which power is transmitted to a sprocket wheel 37 on 40 the feed roll shaft 27 by a sprocket chain 38. In order that the sprocket chain may be kept taut, one of the arms 29 is angularly disposed as shown, and at its angles 45 or corners is provided with a takeup or tension idler roll 39 which may be adjusted bodily to vary the tension on the sprocket chain. The feed roll is prevented from descending so far as to engage the feed 50 table, by the engagement of the arms 29, 29, with stops 40 formed on the frame, as shown in Figure 1.

Power is transmitted to the rotary knife shaft 14, which is the prime power shaft 55 of the machine, by belt pulleys which may be driven from a counter-shaft or from a separate motor as desired. We have shown this shaft as being provided with a loose pulley 41 and a fast pulley 42, to either of

which a suitable belt may be shifted. We 60 regard it as desirable to employ in connection with the shaft a heavy momentum wheel 43 to ensure the severing of the staple when the knives come in contact therewith. Wool is difficult to cut, and, unless the momentum wheel is employed, the rotary knife itself must be of such size and weight as to afford the necessary momentum to ensure the severing of the staple. 65

Practical experience with the use of a 70 machine as herein illustrated has demonstrated that it is entirely satisfactory for the purposes herein mentioned.

The staple, which is severed by the knives, is thrown downwardly along a 75 curved apron 44 and may be received in any suitable receptacle or on a conveyor as desired. The knife itself is preferably protected by a cover comprising a movable section 46 which may be swung to the left in 80 Figure 2 so as to rest upon a stop 47 and thus expose the rotary knife for the removal or sharpening of the blades or for cleaning the knife from accumulated staple and is supported, when swung over the 85 knife, out of contact therewith, by a stop pin 50 with which contacts an extension 51 of the section 46.

What we claim is:—

1. A machine of the class described comprising cutting mechanism, a feed table leading to said mechanism, a shaft beneath said feed table, arms pivoted to said shaft, one of said arms being angular, a feed roll journaled in the free ends of said arms, means to drive said mechanism, means to drive said shaft from said mechanism, a sprocket chain for driving said roll from said shaft, and a chain tightener carried by the angular portion of said angular 90 arm. 95

2. A machine of the class described comprising cutting mechanism, a feed table leading to said mechanism, a shaft beneath said feed table, arms pivoted to said shaft, one of said arms being angular, a feed roll journaled in the free ends of said arms, means to drive said mechanism, means to drive said shaft from said mechanism, a flexible connection for driving said roll from said shaft, and a tightener for said connection carried by the angular portion of said angular arm. 105 110

In testimony whereof we have affixed our signatures.

JOHN W. DAHL,
EDWARD D. MORGAN.
